UNITED STATES PATENT OFFICE.

JOHN K. STEWART, OF CHICAGO, ILLINOIS.

CLIPPER OR SHEARING-TOOL.

SPECIFICATION forming part of Letters Patent No. 689,241, dated December 17, 1901.

Application filed January 4, 1901. Renewed October 21, 1901. Serial No. 79,344. (No model.)

To all whom it may concern:

Be it known that I, JOHN K. STEWART, a citizen of the United States, residing at Chicago, in the county of Cook and State of Illinois, have invented certain new and useful Improvements in Clippers or Shearing-Tools, of which the following is a specification, reference being had to the accompanying drawings, forming a part thereof.

10 This invention relates to improved means in a shearing-tool or clipper for maintaining equal pressure between the cutters at all the several fingers or cutting-points and at all points of its operation and for easing the action of the cutters upon each other without causing liability of said cutters to be separated by foreign substances, preventing their operativeness, and in respect to those features and as an improvement upon a form of 15 device shown in my Patent No. 665,553, dated January 8, 1901, my said invention consisting of specific devices for this purpose, which are set out in the claims.

In the drawings, Figure 1 is a longitudinal 20 vertical section of my improved shearing-tool. Fig. 2 is a plan of the same with the cap-plate removed. Fig. 3 is a detail section at the line 3 3 on Fig. 1. Fig. 4 is a detail plan of a portion of the cutter-operating lever and 25 appurtenances, showing a modification. Fig. 5 is a detail vertical longitudinal section of the tool in the modified form shown in Fig. 4, the plane of such section being denoted by the line 5 5 on Fig. 4.

30 A is the body, on which the operating parts are journaled and mounted and which carries rigid with it at the forward end the comb or fixed cutter B.

C is the operating-shaft, which is journaled 35 in the handle A² of the body and actuates the main lever D by the customary crank-pin and roll c, operating in the vertical channel D' at the rear end of the lever D. The lever D is fulcrumed on a post A³, rigid with the body

40 A. It is bifurcated forward of its bearing on the pivot-post. Toward the forward end of the bifurcation the arms thereof are connected at the upper side by a cross-bar D². In the space between the fork-arms D³ D³ and under the cross-bar D² the lever-arm E extends, 45 said lever-arm being spread or forked at its forward end, terminating in the bearing-fin-

gers E' E', which rest upon the oscillating cutter G toward the opposite ends of the latter and having just behind said bearing-fingers the pins e e, which take into the oscillating cutter, thereby constituting said lever-arm the medium by which the operating-lever D communicates movement to the oscillating cutter.

H is a supplemental lever-finger, which is pivoted at h to the lever-arm E and extends forward from its pivot under or in a slot or channel E² of the lever-arm E, protruding between the fingers E' E' of the latter and bearing upon the middle tooth G² of the cutter G. A pivot H' connects the supplemental lever-finger H pivotally with the operating-lever D, said pivot extending through the fork-arms of the lever D a little forward of the position 70 of the cross-bar D², and said pivot also takes through the lever E at the slightly-elongated slot e² e² in the portion of the lever constituting the walls of the channel in which the finger H is guarded.

A' is a cap which constitutes the upper part of the case A and closes it above.

J is a steel plate, which closes an aperture in the cap immediately above the cross-bar D², said plate being held to the cap by the bolts 80 j j, which also hold the cap to the remainder of the body or case A. The under surface of the plate J is parallel with the plane of contact of the cutters, and the upper face of the cross-bar D² is designed to be also in that 85 plane, and is finished so as to move with minimum friction on said plate J as the operating-lever D oscillates. The pivotal aperture in the finger H is also enlarged from the middle toward both ends, being made slightly hour-glass shaped, permitting thereby a slight oscillation of the said finger, and thereby of the 90 lever E, about its longitudinal axis, in addition to its lever action about said pivot.

F is the adjusting-screw or pressure-screw. 95 It is screwed through the lever E toward the rear end of the latter, said lever being provided with a boss E⁴, extending upward to afford the screw a long bearing in said lever, and the screw at the lower end impinges upon 100 the operating-lever D, which has a web d³ thrown across the bottom of the gap between the fork-arms D³ D³ for this purpose. The under edge of the head F' of the screw F is

serrated, and a spring-dog L is attached to the operating-lever D, arranged to engage the serrations to lock the adjusting-screw at any position to which it may be adjusted. The 5 cap A' has an aperture A¹⁰ to accommodate the adjusting-screw and so much of the spring-dog L as it is necessary to have protrude through the cap to properly engage the head of the screw. It will be seen that by screwing 10 down the adjusting-screw F the rear end of the lever-arm is elevated, and the fingers E' E' at the forward end, resting on the oscillating cutter G and pressing it on the fixed cutter B, cause an upward pressure on the pivot 15 h of the lever-finger H, which in this action fulcrums at its pivotal connection to the operating-lever D, which is effected by means of the pivot-pin H', and such finger is thus forced down at its forward end onto the cutter G, 20 while the reaction of said lever-finger H at its pivotal connection at its rear end to the lever E causes that lever to be forced downward also at its forward end or fingers E' E', said lever in this action fulcruming on the end 25 of the adjusting-screw F, where said screw impinges or is stepped upon the web d³ of the operating-lever D. The relative positions of the pivots h and H' and the step or bearing-point of the end of the screw F upon 30 the web d³ are such that the pressure of the teeth of the cutter G, which are pressed upon respectively by the fingers E' E' of the lever-arm E and by the terminal of the lever-finger H, is substantially equal upon the fixed 35 cutter or comb B. It is designed that the two cutters should be held together by unyielding or inelastic pressure, and the pressure-screw F is designed to be adjusted to cause this perfect contact with barely-perceptible pressure 40 without springing the parts, so as to cause any tendency of the cutter-teeth G', G', and G³ of the oscillating cutter springing down between the teeth of the fixed cutter or comb B, as there might be under an elastic pressure by 45 reason of the slightly-hollow contour of said cutter-teeth, said hollow being not perceptible in the drawings. With such elastic pressure either the cutters are held together with such slight force that a hair or wool fiber frequently is entered between them, so as to hold 50 them apart, thus destroying their power to cut reliably, or if the pressure is too great to permit such an occurrence it causes the teeth of the oscillating cutter to spring down between the teeth of the fixed cutter and so to 55 cause the teeth of the opposed teeth to cut each other and so become very rapidly rounded and dulled.

In the structure above described all the 60 parts by which the pressure is transmitted to the cutters are as rigid as possible and the distance between the bearing-points as short as possible, so that the spring of the parts is reduced to a minimum, and by this means, although at the point at which the pressure reacts against the case—that is, where the bar D² bears against the under side of the plate

J—the construction necessitates sliding friction, a very easy action is obtained and one which causes the minimum wear at the plate 70 J. By arranging this plate to be applied from the outside and to be a detachable cap susceptible of being thoroughly finished and hardened this bearing is made very easy to keep in order. An especial advantage of construction at this point arises from the fact that the bearing-surface of the operating-lever D upon the case faces downward, so that it is not liable to accumulate dust and dirt and hairs, which would interfere with the action and 80 cause the plate to be cut away. It is essential that all the parts which bear upon the oscillating cutter shall have opportunity to rock at the step-bearing at the end of the pressure or tension screw F on the web d³, so 85 that said oscillating cutter may be accommodated in all parts to the upper part of the fixed cutter or comb. It is also essential that the oscillating cutter should receive the full range of oscillating or reciprocating movement which the operating-lever D is calculated to give it, and for this reason there should not be any lateral play allowed to the lever-arm E with respect to the main operating-lever D, of which it is practically the extension. In order to afford the rocking movement, which is necessary, and also to prevent any lateral movement, which is undesirable, I have provided the detail structure above 95 described, consisting of forking the forward portion of the operating-lever D and giving to the oscillating lever E a stem which extends between the arms of such fork and which at two points—to wit, at the rear end and at least where the pivot H' extends through 100 said stem—is made to fit closely between the fork-arms, so that it has no lateral movement, and in order that said stem may be of proper form to permit the oscillation of the lever D about a longitudinal axis I make it substantially cylindrical or circular about a longitudinal axis, the rear end being also preferably rounded about a horizontal axis, and thereby becoming approximately a spherical knob, as seen at e⁴, so that while fitting tightly between the arms of the fork it shall be free to 105 oscillate about the longitudinal axis and also to move up and down slightly as necessary in order to permit the movement for adjusting the parts to contact with the pressure caused by the screw F, and in order that the oscillation about the longitudinal axis may be consistent with the fact that such oscillation or rocking movement takes place by rocking upon the step of the screw F where the latter bears upon the web B³, I construct the parts so that the point of bearing is substantially in the axis of the cylindrical stem of 110 said lever-arm E.

The bearing-surface with which the operating-lever is provided in position for bearing upwardly against the downwardly-facing plate J may be the surface of antifriction-rollers (one or more) suitably journaled on 115

said operating-lever, as in the modification illustrated in Figs. 4 and 5, wherein said rollers are denoted by the letters $d^1 d^2$. These rollers should be journaled with their axes 5 radial to the axis of oscillation of the lever and should be tapered slightly, so as to roll naturally in the arc which the roller is caused to describe by the oscillation of the lever.

By the term "bearing-surface" used in the 10 claims to denote the surface which bears upwardly against the downwardly-facing plate J, I design to be understood as indicating in-differently the surface of the integral operating-lever or the surface of the antifriction- 15 roller, which may be mounted on such lever, and thereby interposed between the integral lever and the plate, to afford the direct contact with the latter.

I claim—

20 1. In a clipper or shearing-tool, in combination with a case or body, the lever for operating the oscillating cutter provided on its side with an antifriction-roller, the upper wall or cap of the case having an aperture above the 25 path of such roller, and a detachable plate applied at such aperture and having its lower face in the plane parallel to the plane of contact of the cutters and arranged to afford bearing for the upper surface of the roller as the 30 lever oscillates.

2. In a clipper or shearing-tool, in combination with the cutter and the main operating-lever, a lever-arm actuated by said main operating-lever, having loose pivotal connections thereto and laterally restrained thereby, but having a limited freedom of oscillation about a longitudinal axis, and of vertical movement with respect to said main operating-lever, the latter having journaled upon 35 its upper side an antifriction-roller exposed upwardly, and the case having a plate having a downwardly-facing bearing-surface parallel to the plane of contact of the cutters, against which such antifriction-roller bears upwardly 40 as the lever oscillates.

3. In a clipper or shearing-tool, in combination with the case or body, the lever for operating the oscillating cutter having mounted upon it and exposed upwardly two antifriction-rollers whose axes converge toward the 45 axis of oscillation of the lever, the upper wall or cap of the case having an aperture above the path of oscillation of said rollers, and a detachable plate applied at such aperture 50 and having its lower face in a plane parallel to the plane of contact of the cutters and arranged to afford bearing for said upwardly-exposed antifriction-rollers.

4. In a clipper or shearing-tool, in combination with the cutter and the main operating-lever, a lever-arm actuated by said main operating-lever having loose pivotal connection thereto and laterally restrained thereby, but having limited freedom of oscillation about a longitudinal axis, and of vertical movement with respect to said main operating-lever, the latter having an upwardly-fac-

ing bearing-surface, and the case having a plate with a bearing-surface parallel to the plane of contact of the cutters, against which 70 the bearing-surface of the main lever presses.

5. In a clipper or shearing-tool, in combination with the oscillating cutter, the main operating-lever; a lever-arm having loose pivotal connection to said main operating-lever 75 and laterally restrained thereby, but having a limited freedom of oscillation about a longitudinal axis, and of vertical movement with respect to said lever, and bearing on the oscillating cutter and constituting the medium 80 by which the main lever actuates said cutter; a screw operating between said main lever and said lever-arm screwed into one of said parts and impinging against the other to adjust the lever-arm in vertical plane about its 85 pivotal connection to the main operating-lever, the latter having an upwardly-facing bearing-surface, and the case having a plate with the bearing-surface parallel with the plane of contact of the cutters, against which 90 the bearing-surface of the main operating-lever is pressed by the action of the screw forcing the cutters into contact.

6. In a clipper or shearing-tool, in combination with the case or body, the oscillating 95 cutter; the main operating-lever fulcrumed on the body; a lever-arm having a stem extending in and laterally restrained by said operating-lever having a loose pivotal connection thereto and limited freedom of oscillation about the longitudinal axis of its stem and of vertical movement with respect to said operating-lever, said lever-arm at the forward end bearing on the oscillating cutter and constituting the medium by which the main 100 lever actuates said cutter; and a screw operating between said lever-arm and said operating-lever, to adjust the former about its pivot to the latter.

7. In a clipper or shearing-tool, in combination with the case or body, the oscillating cutter and the main operating-lever; a lever-arm which at the forward end bears upon the oscillating cutter toward the opposite ends of the latter; a supplemental lever-finger pivoted at its rear end to said lever-arm, and at its forward end bearing upon the oscillating cutter intermediate the ends of the latter, said lever-finger being pivoted to the main operating-lever forward of its pivotal attachment to the lever-arm, and having at its said pivot to the operating-lever limited freedom of oscillation about a longitudinal axis, and an adjusting-screw, operating between the rear portion of said lever-arm and the operating-lever, being screwed into one of said parts and impinging against the other, to press the oscillating cutter against the fixed cutter.

8. In a clipper or shearing-tool, in combination with the case, the oscillating cutter and the main operating-lever, a lever-arm carried by the main operating-lever and laterally restrained thereby, and at its forward

end bearing on the oscillating cutter toward the opposite ends of the latter; a supplemental lever-finger pivoted at its rear end to said lever-arm, and at its forward end bearing upon the oscillating cutter intermediate the ends of the latter; said supplemental lever-finger being pivoted to the operating-lever forward of its pivotal connection to said lever-arm, and having at its said pivotal connection to the operating-lever limited range of oscillation about a longitudinal axis; said operating-lever being pivoted on a post rigid with the case, and having an upwardly-facing bearing-surface, and the case having its plate 15 with the bearing-surface parallel with the plane of contact with the cutter, against which the bearing-surface of the operating-lever may be pressed; an adjusting-screw, operating between the operating-lever and 20 said lever-arm, screwed into one of said parts and impinging against the other to force the oscillating cutter upon the fixed cutter.

9. In a clipper or shearing-tool, in combination with the case or body having the fixed cutter, the oscillating cutter; a main operating-lever fulcrumed on a rigid post of the case; a lever-arm which at its forward end bears 25

upon the oscillating cutter toward the ends of the latter and constitutes the medium by which the operating-lever actuates said cutter; a supplemental lever-finger pivoted to said lever-arm and extending forward from its pivot and at its forward end bearing upon the oscillating cutter intermediate the ends of the latter; a pivot which connects said lever-finger to the operating-lever, said pivot extending through the lever-arm; the pivot-apertures in said lever-arm and said supplemental lever-finger being enlarged both ways 30 from a middle point in the latter, to permit 35 said lever arm and finger to have a limited range of oscillation about a longitudinal axis, and an adjusting-screw operating between said lever-arm and said operating-lever at the rear part of the former to force its forward 40 end down upon the oscillating cutter.

In testimony whereof I have hereunto set my hand, at Chicago, Illinois, in the presence of two witnesses, this 31st day of December, A. D. 1900.

JOHN K. STEWART.
